Ch. Farber.

Attorney

UNITED STATES PATENT OFFICE.

MAX NEFT, OF SEATTLE, WASHINGTON.

STEEL FOR GUITARS.

1,342,718.

Specification of Letters Patent.

Patented June 8, 1920.

Application filed August 13, 1919. Serial No. 317,304.

To all whom it may concern:

Be it known that I, MAX NEFT, a citizen of the United States, residing at Seattle, in the county of King and State of Washington, have invented certain new and useful Improvements in Steels for Guitars, of which the following is a specification.

This invention relates to new and useful improvements in steels for Hawaiian guitars.

An object of the invention is to produce such a steel which eliminates the rasping sound often caused by the steel sliding over the wire.

In the present form of steel, the construction is solid and the steel, as drawn over the strings of the guitar, causes a rasping sound and an uneven tone. The bass strings being wire wound have a certain roughness of surface and consequently wear with a certain degree of rapidity when a solid steel is used.

To overcome the above objection, I have supplied a steel, the contact face of which is a roller suitably mounted and which accordingly will not rasp but gives a smooth mellow tone and practically eliminates all wear upon the strings.

Other objects and advantages of the invention will be apparent during the course of the following description.

In the accompanying drawings forming a part of this specification and in which like numerals are employed to designate like parts throughout the same,

Figure 1 is a perspective showing my steel in use upon a guitar,

Fig. 2 is an enlarged perspective of the steel.

Fig. 3 is an end elevation thereof,

Fig. 4 is a side elevation, partly in section, and,

Fig. 5 is a section taken on line 5-5 of Fig. 4.

Referring now more particularly to the drawings, the numeral 10 indicates a guitar and the numeral 11, a steel for use upon the strings 12, of the guitar.

The steel 11 comprises a body portion 12' having a rabbet 13, formed in one of the longitudinal edges thereof. The rabbet 13 in the body portion forms two depending

arms 14 and 15, between which is positioned a rotatable roller 16. The surface of the roller 16 is extremely smooth in finish, and the roller is provided with a central aperture 17. The arm 14 is supplied with a counter-sunk aperture 21 and the arm 15 is provided with a threaded aperture 22. A shaft 18 having an enlarged head 19 and a threaded end 20 extends through the arm 14, 60 roller 16, and engages with its threaded end, the threaded aperture 22 of the arm 15.

It will readily be seen that the roller 16 is rotatably supported and will in consequence, give a smooth motion to the steel 65 and consequently, a smoother and more even tone to the instrument.

It is to be understood that the form of my invention herewith shown and described is to be taken as a preferred example of the 70 same, and that various changes in the shape, size, and arrangement of parts may be resorted to without departing from the spirit of the invention or the scope of the subjoined claims.

Having thus described my invention, I claim:

1. A steel for stringed instruments, comprising a body portion, and a smooth roller mounted in one edge of said body portion 80 and adapted to contact with the strings of the instrument to be played.

2. A steel for stringed instruments, comprising a body portion having a recess formed in one edge, and a smooth roller 85 mounted in said recess and adapted to contact with the strings of the instrument to be played.

3. A steel for stringed instruments, comprising a body portion, outwardly extending arms arranged on the body portion, said arms being positioned to form a recess in the body portion, and a smooth roller mounted in said recess and adapted to contact with the strings of the instrument to be 95 played.

In testimony whereof I affix my signature in presence of two witnesses.

MAX NEFT.

Witnesses:

W. E. FROUDE,
H. M. CRAMER.
